DISPLAY RACK

Lindell D. Watley, Hastings, Nebr., assignor to
Ag-Tronic, Inc., Hastings, Nebr.

Filed Feb. 28, 1972, Ser. No. 230,199

Term of patent 7 years

Int. Cl. D6—06

U.S. Cl. D6—180

FIG. 1

FIG. 2

FIG. 3

FIG. 4

FIG. 5

FIG. 1 is a perspective view of a display rack showing my new design;

FIG. 2 is a top plan view thereof;

FIG. 3 is a side elevational view thereof, wherein the other side is substantially a mirror image thereof;

FIG. 4 is a front elevational view thereof; and

FIG. 5 is a perspective view of a display rack showing a modified form of my new design.

I claim:

The ornamental design for a display rack, substantially as shown and described.
